UNITED STATES PATENT OFFICE.

FRED J. DAVIS, OF NORTHFIELD, VERMONT.

DESIGN FOR A MONUMENT.

44,362.

Specification for Design.

Patented July 22, 1913.

Application filed March 15, 1913. Serial No. 754,638. Term of patent 14 years.

To all whom it may concern:

Be it known that I, FRED J. DAVIS, a citizen of the United States, residing at Northfield, in the county of Washington and State of Vermont, have invented a new, original, and ornamental Design for Monuments, of which the following is a specification, reference being had to the accompanying drawing, forming a part thereof.

Figure 1 is a perspective view of a monu-

ment showing my new design; and Fig. 2 is a side elevation of the monument.

I claim—

The ornamental design for a monument as shown.

FRED J. DAVIS.
